UNITED STATES PATENT OFFICE.

PETER BACHER, OF CANTON, OHIO.

CUPOLA-FURNACE.

SPECIFICATION forming part of Letters Patent No. 712,472, dated November 4, 1902.

Application filed March 17, 1902. Serial No. 98,492. (No model.)

To all whom it may concern:

Be it known that I, PETER BACHER, a citizen of the United States, residing at Canton, in the county of Stark and State of Ohio, have 5 invented certain new and useful Improvements in Cupola-Furnaces; and I do hereby declare that the following is a full, clear, and exact description of the same, reference being had to the annexed drawings, making a 10 part of this specification, and to the figures of reference marked thereon, in which—

Figure 1 is a side elevation showing one division or hinged section open, also illustrating a portion of the base broken away. Fig. 15 2 is a horizontal section. Fig. 3 is a view showing portions of the hinged sections of the furnace. Fig. 4 is a view showing a portion of one of the hinged sections of the furnace.

20 The present invention has relation to cupola-furnaces; and it consists in the different parts and combinations of parts herein-after described, and particularly pointed out in the claims.

25 Similar numerals indicate corresponding parts in all the figures of the drawings.

In the accompanying drawings, 1 represents the supporting posts or pillars, which are supported upon suitable foundations, 30 such as 2, and are formed of a height to correspond substantially with the extreme height of the hinged sections of the furnace. Upon the top or upper ends of the posts or pillars 1 is located a top plate 3, to which top plate 35 is connected the fixed dome-section 4, said dome-section extending a short distance below the bottom or under side of the plate 3. To the dome-section 4 is attached in a convenient and well-known manner the furnace-40 stack 5.

At a suitable distance from the bottom or lower ends of the posts 1 is located the furnace base-plate or frame 6, which is provided with the usual center opening 7, which center opening is for the usual purpose and of course is to be closed when the furnace is to be brought into use by the ordinary hinged members 8, or, if desired, a sliding plate may take the place of the hinged members 8. This 45 construction being common in furnaces of this class needs no specific description here; but in order to carry out the perfect working

of the furnace it is necessary to provide means for closing the bottom of the furnace proper. Upon the base-plate 6 are located the hinged 55 sections 9, which hinged sections are convexo-concavo and the inner or concave side thereof lined with suitable fire-brick, such as are used in the manufacture of furnaces of this class. The sections 9 are hinged together by means 60 of suitable hinges, such as 10, which of course must be of sufficient strength to properly hold the hinged edges of the convexo-concavo sections together. To the opposite side of one of the hinged sections 9 are attached and se- 65 curely fixed any desired number of staples, such as 11, and upon the other hinged member are secured the corresponding number of hasp-bars 12, which hasp-bars receive the staples when the hinged sections are 70 brought together to produce a continuous cylindrical shell and are securely held in such position by means of suitable keys 13. In the drawings the keys are shown located in the staples 11; but before the hasps are 75 brought into position to properly close the hinged sections 9 it will be understood that the keys 13 must be removed from the position shown in the drawings and the keys placed in the staples after the hasps have 80 been brought into such a position that the staples will extend through the slots. For the purpose of providing a means for easily moving the hinged sections 9 the base-plate 85 6 is provided with the channel or groove 14 and in which channel or groove are located any desired number of antifriction-balls 15, which antifriction-balls are located directly under the flanged plates 16, which flanged plates come and go with the hinged sections 90 9, and for the purpose of providing the means for supporting the hinged sections now when they are open the base-plate 6 is provided with the extensions 17, which extensions are 95 supported by suitable posts 18, said posts being located and arranged substantially as shown in the drawings.

The inner melting-pot 19 is substantially of the form shown and is made of the material commonly used for melting metals re- 100 quiring a high degree of temperature, and for the purpose of supporting the melting-pot 19 when the same is filled or loaded the supporting-post 20 is provided, which sup-

porting-post is located directly under the bottom or lower end of the melting-pot 19, and said post is supported by the bar or plate 21, which comes on top of the base-plate 6 and 5 of course above the hinged members 8, so that when the hinged members are permitted to fall, as illustrated in the drawings in Fig. 1, the melting-pot will be supported; but of course it will be understood that the hinged 10 sections 8 are not to be released when the melting-pot contains metal either in a solid or a melted condition.

For the purpose of preventing the melting-pot 19 from tipping the hinged sections 9 are 15 provided with the inward-projecting stays 22, which are fixed through the hinged sections 9 and are formed of such a length that when said hinged sections are closed the inner ends of the stays 22 will come against or nearly 20 against the melting-pot 19. It will be understood that the stays 22 are to be formed of the same material as the melting-pot 19, this kind of material being used for the purpose of preventing the stays from becoming 25 displaced or destroyed during the melting process.

By the use of my improved furnace I am enabled at one and the same time to melt two kinds of metal—for instance, steel and iron 30 or brass and iron—owing to the fact that there is no direct communication between the melting-pot 19 and the intervening space between the outer portion of the melting-pot and the inner portions of the hinged sections 35 9.

Heretofore it has been difficult to place a melting-pot in a cupola-furnace owing to the fact that the furnace proper must be turned down or the top removed in order to place 40 the melting-pot in position. By my peculiar arrangement I am enabled to easily remove the outer shell of the furnace, or, in other words, to open the same, so as to provide room for sliding the melting-pot into position, and when the melting-pot has been 45 brought into position the outer wall of the furnace can be quickly brought into its relative position and the furnace is ready for use. The upper portion of the furnace— 50 that is to say, the dome 4 and the plate 3—is supported independent of the walls of the furnace proper and that when the hinged sections 9 are turned upon their hinges the dome and its supporting-plate, together with the 55 stack of the furnace, remain in their fixed position and are never disturbed for any purpose whatsoever so far as the working of the furnace is concerned and the changing of the melting-pot.

60 It will be understood that the space between the melting-pot 19 and the outer shell of the furnace proper can be utilized in the same manner that is employed at the present time—that is to say, the ore, coke, and other 65 materials can be placed in position around the melting-pot 19 and when the metal is melted it is drawn from the furnace in the

usual manner; but when the metal in the melting-pot is ready to be withdrawn the plug is removed and the metal allowed to flow 70 through the delivery pipe or spout 23, which delivery-pipe is formed of such a length that it will pass through the opening 24, which opening is located in one of the hinged sections 9.

For the purpose of delivering the proper 75 blast any desired number of blast-pipes, such as 25, are employed, which blast-pipes are of course connected to a fan or fans in the usual manner. The blast-pipes are connected to the annular channels 26 and 27, which channels may be provided with the usual inspecting-apertures 28.

For the purpose of conveying material into the melting-pot 19 the spout 29 is provided, which spout is located at a point so as to prop- 85 erly charge the melting-pot.

For the purpose of providing means for skimming and removing foreign substances that may accumulate upon the top of the material contained in the melting-pot a pipe 30 90 is provided and properly connected, which pipe extends through a suitable aperture, such as 31, formed in one of the hinged sections 9.

It will be understood that the ordinary closing-plugs are to be employed to close the outlet-apertures of the melting-pot and the outer melting-chamber, which are operated in the usual manner and are held in place in any common and well-known way. It will also be 100 understood that the floor upon which my improved furnace is to be located should be so formed that the different apertures for removing the molten metal can be of easy access, this being done by slanting the floor so 105 as to allow room for the proper operation and working and save any lifting to any extent of the molten metal. This being common needs no special description here.

The blast-passages 32 and 33 are inclined 110 downward through the hinged sections 9 and are so formed for the purpose of preventing the material from passing outward and for the purpose of protecting the inner ends of the blast-passages.

The brick forming the lining for the hinged sections 9 should be set over or extended beyond the inner ends, so that in charging the furnace or by the dropping of the material in the furnace it will not be caught by the inner 120 ends of the blast-passages 32 and 33.

For the purpose of properly holding the brick constituting the lining of the hinged sections 9 any desired number of metallic strips 34 are employed and are located at such 125 intervals as to properly retain the brick and prevent the same from becoming detached during the time the hinged sections 9 are swung upon their hinges. These bars are supported through the metal casing of the 130 hinged sections 9.

The upper channels 27 are for the purpose of providing a blast to the upper portion of cupola between the hinged sections 9 and the

melting-pot 19, and for the purpose of regulating the blast dampers 27^a are provided, which dampers are operated in the usual manner.

5 For the purpose of holding the hinged members 8 in a closed position a post 8^a is employed, and when it is desired to have an up-blast or a draft grates may take the place of the hinged members 8, this simply being a 10 change from the hinged members 8 to the hinged grate members.

For the purpose of supplying coke and other material to the cupola between the melting-pot and the hinged members 9 suitable doors, 15 such as 10^a, are used. In the drawings I have illustrated one of these doors; but it will be understood that any desired number may be employed.

It will be understood that the stays 22 and 20 the posts 20 are to be formed of the same material as that used in the construction of the melting-pot, which material is what is known as "black lead" or "graphite."

By my peculiar construction I am enabled 25 to use the melting-pot and melt the metal contained therein by the heat generated in the cupola proper between the hinged sections or members 9 and the outer periphery of the melting-pot and that the melting-pot may be 30 changed any desired number of times, this being a great advantage, owing to the fact that different kinds of metal may be melted at one and the same time and each kind independently melted.

35 Having fully described my invention, what I claim as new, and desire to secure by Letters Patent, is—

1. In cupola-furnace of the class described, a base-plate supported in proper elevation, 40 pillars or posts carrying a top plate having connected thereto a dome-section, said dome-section extending below the bottom or under

side of the plate, hinged sections normally located below the top plate and above the base-plate and said sections hinged together, and 45 means for securely holding the hinged sections in a closed position, substantially as and for the purpose specified.

2. In a furnace of the class described a base-plate supported in proper elevation by pillars 50 or posts, and the pillars or posts extended above the base-plate, a top plate secured to the pillars or posts, furnace-sections hinged together, and located between the base-plate and the top plate, a dome carried by the top 55 plate, and a melting-pot located normally within the hinged sections, means for supporting the melting-pot in proper elevation, substantially as and for the purpose specified.

3. The combination of a base-plate, posts 60 or pillars carrying a top plate and the top plate provided with a dome-section, hinged furnace-sections provided with brick, means for locking the sections together and the base-plate provided with channels and the chan- 65 nels having antifriction-bearings, substantially as and for the purpose specified.

4. In a furnace of the class described a base-plate and a top plate spaced therefrom, said top plate provided with a dome-section held 70 in elevation independent of the furnace section or sections or wall, and the furnace sections or wall adapted to be moved laterally between the base-plate and the dome-section, and a melting-pot located within the furnace- 75 wall and spaced therefrom, substantially as and for the purpose specified.

In testimony that I claim the above I have hereunto subscribed my name in the presence of two witnesses.

PETER BACHER.
